COMMUNICATION SYSTEM

Thomas W. W. Holden, Fort Wayne, Ind., assignor
to The Magnavox Company, Ltd., Fort Wayne,
Ind., a corporation of Indiana

Application August 19, 1942, Serial No. 455,296

11 Claims. (Cl. 179—1.5)

This invention relates to communication systems, and more particularly to a communication system employing a much narrower band of audio frequencies than has been used in the past. Still more particularly the invention relates to a secret communication system.

The communication system of this invention may be used to overcome fading or atmospheric disturbances, as well as for secrecy purposes. Such a communication system may also be used to provide a greater number of transmission channels than heretofore available.

It is, accordingly, an object of the invention to provide a communication system, more particularly for transmitting speech, by which a much narrower band of audio frequencies may be employed to transmit the message or speech.

An ancillary object of the invention is to provide a secret communication system, more particularly for voice currents, and by means of which a greater number of transmitting channels may be made available while at the same time the secrecy of the conversations is maintained.

A further object of the invention is to provide such a communication system by means of which the receiving instrumentalities or reproducers may be more sharply and selectively tuned to the transmitting carrier or signal so that noise or static may be more effectively eliminated.

In general, the invention contemplates a communication system wherein the messages or signals, and particularly voice currents, are subdivided into sections or syllables at the transmitting station. Each section or syllable is reduced in frequency, as, for example, by the elimination of repetitious portions of the syllabic wave trains, and transmitted at the reduced frequency. At the receiving station each section or syllabic wave train is increased in frequency, as by suitable repetition of the received syllabic wave train, and thereby the syllables are restored to their original wave forms by appropriate apparatus which is set to function in predetermined speed relation with the apparatus at the transmitting station.

Further objects and novel features of the invention will be apparent from the following description when taken in connection with the accompanying drawings, wherein—

Figure 1 diagrammatically shows one form of communication system embodying the invention;

Figure 2 is a view in elevation of a frequency divider forming part of the transmitting apparatus;

Figure 3 is a view in generally vertical section

taken substantially along the line 3—3 of Figure 2;

Figure 4 is a fragmentary view in generally horizontal section taken along the line 4—4 of Figure 2;

Figure 5 is an enlarged fragmentary view in perspective of a portion of the frequency divider of Figures 2 and 4;

Figure 6 is a fragmentary view in vertical section through the frequency multiplier unit of the receiving station; and

Figure 7 is a reproduction of an oscillographic record, useful in understanding the invention, and represents the wave trains making up a typically spoken word.

All tones or sounds consist of a repetition of wave trains of a definite pattern, as illustrated in Figure 7 in respect to the word "farmers." Since, therefore, as can be seen from Figure 7, any tone, sound, or syllabic wave train consists of one or more sets of several similar wave patterns or trains, any one pattern is characteristic of a whole series of waves. The present invention utilizes this discovery to provide a new communication system by means of which only one-tenth of each tone, or sound, or set of syllabic wave trains is necessary for transmission and the remaining nine-tenths of each may be provided at the receiving station by reconstruction from the characteristic wave patterns.

As indicated in Figure 1, a communication system embodying this invention may comprise a microphone 2 from which the audio or voice currents, after amplification by the amplifier 4, are used to excite a frequency divider or reducer 6. The frequency divider 6 feeds to a modulator 8 only characterizing wave patterns and the modulator, in turn, effects modulation of a radio frequency carrier and feeds the modulated radio frequency signal to the transmitter 10 feeding the transmitting antenna 12. The radio frequency signals received by the receiving antenna 14 are fed to radio receiver 16 which, in turn, supplies the rectified signals or message portions to a frequency multiplier 18 by means of which the audio or voice currents are reconstructed and fed to the phones 20. Since any voice currents obtained from the radio signal without multiplication in the same ratio as the division or reduction affected at the transmitting station, will be unintelligible, the secrecy of the communication is maintained.

This system can be used with telephone circuits, as well as radio circuits, either wired or wireless. It will be evident, of course, that if

sed with telephone circuits, suitable terminal apparatus will be fed from the frequency divider 6 at the transmitting end and appropriate terminal apparatus will be used at the receiving end to feed the frequency multiplier 18.

The frequency divider or reducer 6 at the transmitting station divides or reduces the voice frequencies by a factor that may be changed to fit the type or characteristics of the transmission system. The frequency multiplier 18 at the receiving station restores or reconstructs the speech or signal to its original form and frequency.

The frequency divider or reducer 6 comprises, as best shown in Figures 2 to 5, a synchronous motor 20 supported on a suitable base or standard 22 and driving rubber wheels or pulleys 24 and 26. The wheel 24 drives a disc 28 fixed to a rotary shaft 30 suitably supported and journaled in posts 32 upstanding from the base or standard 22. The rubber wheel 26 engages the annular flange 34 of a drum 36 to the periphery of which there is secured the usual magnetic recording tape 38. A recording coil or head 40 is disposed in radial juxtaposition to the tape 38 and applies the message to this tape. This coil is fed by the amplifier 4, as indicated in Figure 1. The drum 36 is mounted loosely on the shaft 30 for rotation relative thereto, but held against axial movement as by the collars 42. A disc 44 is fixed to the shaft and positioned within the cylinder formed by the recording tape 38.

The disc 44 carries take-off or pick-up coils 46, 48 and 50. Each pick-up coil is mounted on the disc for angular movement relative thereto in a direction substantially radially of the disc. The mounting means may comprise a mounting plate 52 to one end of which the coil is fastened, the other end of the plate being pivoted to the disc 44 as by a stud or bolt 54. A spring strip 56 is secured at one end, as by block 58, to the disc 44 above the plate 52 and at its other free end bears against the upper side edge of the plate 52 so as to normally urge this plate away from the recording tape 38. Movement of the plate inwardly of the disc may be limited by a stop pin 60, or the like, secured to the disc on the opposite side of the plate 52. Each pick-up is short circuited when it is out of engagement with the recording tape. This may be accomplished by connecting the leads 62 and 64 to each pick-up to a shunting switch 66. The switch 66 may comprise a resilient contact blade 68 fixed at one end to a terminal block 70 fastened to the disc above the plate 52, and an adjustable contact screw 72 threaded into a block 74 fastened to the disc. Any suitable means may be used to mount the contact blade and screw on the disc 44. The blade 68 is so positioned that at its free end it engages the upper side edge of the plate 52 so that as the plate moves radially inwardly of the disc the blade 68 engages the contact screw 72 and completes the shunting circuit around the coil or pick-up magnet 46. The pick-up coils are moved radially outwardly in succession to engage successively the recording tape 38 with which they are held in engagement for a predetermined interval by a stationary cam bar 76 concentric to the disc and drum and formed at its upper free end with a cam surface 78 which, on being engaged by a cam lug 80 depending from the lower edge of the plate 52, moves the pick-up coil or magnet into engagement with the recording tape 38. The bar 76 may be formed integrally with a bar 82 extending upwardly from the

base or platform 22 and formed with an offset arm 84 permitting the bar 76 to be positioned in close juxtaposition to the outer face of the disc 44. The bar 76 is preferably of such arcuate extent as to permit one pick-up unit to be moved by its spring out of operative relation with the tape at the same instant as the next following pick-up unit is moved by the bar into operative relation with the recording tape. The several pick-up coils 46, 48 and 50 are connected in series by their respective leads 62 and 64 and to slip rings 86 and 88 with which cooperate brushes 90 and 92 connected by leads 94 to the modulator 8.

The diameters of the wheels 24 and 26 and of the disc 28 and the annular flange 34 of the drum 36 are so proportioned that the pick-ups rotate at a speed less than the peripheral speed of the tape 38. Preferably the pick-ups are made to rotate at a speed which is nine-tenths of the peripheral speed of the recording tape.

The message recorded on the recording tape 38 may be wiped therefrom or extinguished as by means of the conventional wiper or extinguishing electro-magnet 96 suitably energized, as by battery 98, the electro-magnet 96 being positioned also in radial juxtaposition to the recording tape and preferably in diametrically opposed relation to the recording coil or magnet 40.

The frequency multiplier 18 is preferably of substantially the same structure as the frequency divider 6 and differs therefrom only in that the driving motor 100 (Figure 6) drives the disc 102, which carries three pick-up coils 104, at a speed which is a multiple of the speed at which it drives the drum 106 carrying the recording tape 108 and drives the pick-ups and tapes in opposite directions. The motor 100 drives the disc 102 through the rubber wheel 110, the disc 112 and the shaft 114, and drives the drum 106 through the smaller rubber wheel 116 which directly engages an annular flange 118 of the recording drum. The signals or message wave patterns are recorded on the tape 108 by a suitable recording coil fed by the receiver 16 and the reconstructed signals are fed from the pick-up coils 104 through leads and slip rings, connected in the same manner as illustrated in Figures 2 and 3, to the phones 20.

By rotating the disc 44 carrying pick-ups 46 at a speed which is less than the peripheral speed of the recording tape 38, the frequency of the signal currents recorded on the tape is, in effect, reduced. If the frequency alone were reduced, then a greater time would be required to send out the full message.

Analysis of vibration forms of words, tones, syllabic wave trains, etc., shows that each word, tone, or syllabic wave train is comprised of one or more sets of repeated wave forms in continuous sequence. Any one wave form of each such set will, therefore, be characteristic of the entire train of identical wave forms, and if each wave form be reduced in frequency, the whole of the wave train may be reconstructed, as far as intelligibility is concerned, by repeating that same wave form at a higher frequency, equal of course to the original frequency of the wave form.

Thus in the present invention only a fraction 70 of the repeated wave patterns is sent out, and the remainder of each wave pattern is supplied at the receiving station by the frequency multiplier which speeds up the frequency by the same amount as it is slowed down by the frequency divider. If, as in the preferred form, the fre-

quency of the signals or messages recorded on the tape is reduced to ten percent of the original recorded frequency, by driving the pick-up magnets 46 to 50 at a speed which is nine-tenths of the peripheral speed of the recording tape, then the signal or message may be reconstructed at the receiving station by driving the magnets 104 at a speed which is nine times the peripheral speed of the recording tape 108. It will be evident that other speed relations between the pick-up magnets 46 to 48 and the recording tape 38 may be employed, and that the message will be reconstructed into intelligible form only at a receiving station at which the pick-up magnets rotate proportionately faster than the recording tape 108.

Since the transmitted carrier is modulated at frequencies which are one-tenth of normal, more transmitting channels may be made available without interference one with the other, and the receivers may be made more sharply selective; in other words, tuned more precisely to the carrier frequency. Fading and static interference will correspondingly be reduced.

Having thus described my invention, what I claim as new and desire to secure by Letters Patent is:

1. The method of transmitting intelligence which comprises subdividing the voice currents to be transmitted into syllabic sections, eliminating repetitious portions of each syllabic section and transmitting the balance at reduced frequency to a distant station, at the distant station increasing the frequency of each syllabic section to its original value and repeating each syllabic section at the increased frequency to reconstitute each syllable of the original voice currents at the transmitting station.

2. The method of transmitting intelligence secretly from a true record wave form of the message to be transmitted which comprises picking up from the record wave form selected portions only at a speed fixed, for at least each transmission, and lower than the speed at which it was originally recorded to reduce the frequencies of the selected portions, transmitting said selected portions at said reduced frequencies to a distant station, and there repeating each selected portion a sufficient number of times at the original frequency at which the message was recorded to restore the message to its original record wave form.

3. The method of transmitting intelligence which comprises making a true record wave form of the message at a definite speed, picking up from the record characterizing portions only of the recorded message wave form at a speed below, and in predetermined ratio to, the speed at which the message was recorded to reduce the frequencies of the picked up characterizing portions, transmitting the characterizing portions at the reduced frequency to a distant station, recording the characterizing portions as transmitted to the distant stations, at a definite speed, and repeatedly picking up each characterizing portion from the last recording at a speed sufficiently higher than the speed of such last recording to restore the message to its original wave form and composition.

4. The method of transmitting intelligence secretly from a true record of the complete message, which comprises picking up characteristic sections only of the syllabic wave trains composing the recorded message and at a reduced frequency, transmitting said syllabic characteriz-

ing sections at the reduced frequency to a distant station and there repeating each syllable characterizing section a sufficient number of times at its original frequency to reform the sections into a reproduction of a complete message.

5. A system for transmitting messages which comprises means for making a true record of the message to be transmitted, means for picking up from the record at least one characteristic portion of each wave train composing the message wave form at a speed such that the pick-up time for the portion of each wave train is substantially the same as the recording time for the entire wave train characterized thereby, whereby repetitious portions of each wave train composing the message wave form are eliminated and the balance picked up at a frequency so reduced that the pick-up of the message is continuous where the recorded message is continuous and discontinuous where the recorded message is discontinuous, means for transmitting said characteristic portions at the reduced frequency to a distant station, means at the distant station for recording said characteristic portions, as transmitted, at the reduced frequency and pick-up means at said distant station for repeatedly picking up each of the said characteristic portions from said last record at a speed sufficiently higher than the speed of the last recording to reconstitute each wave train from its characteristic portion and reproduce the message at its original wave form and frequency composition.

6. In an apparatus receiving unintelligible message characterizing wave sections transmitted at reduced frequencies, a traveling recording tape driven at a preselected speed, means for recording on said tape said message characterizing sections at the reduced frequency of transmission, a plurality of traveling pick-ups, means driving said pick-ups at a speed higher than the speed of the tape in the predetermined ratio of the original message frequencies to the reduced transmitted message frequencies, and means rendering said pick-ups successively effective in timed relation to pick up repeatedly each message characterizing section to reconstitute from the characterizing sections of reduced frequency the original message in its wave form and frequency composition.

7. In an apparatus for receiving unintelligible, uninterrupted syllable characterizing wave cycles of a message transmitted at reduced frequencies, a traveling recording tape driven at a preselected speed, means for recording on said tape said uninterrupted syllable characterizing wave cycles at the reduced frequencies of transmission, and traveling pick-up means traveling at a speed higher than the speed of the tape in the ratio of the original message frequencies to the reduced transmitted message frequencies and constructed and arranged to repeatedly pick up each uninterrupted syllable characterizing wave cycle to intelligibly reproduce each syllable of the original message at its original frequencies.

8. In an apparatus receiving unintelligible, uninterrupted message characterizing sections transmitted at reduced frequencies, an endless recording tape driven continuously at a preselected speed, means for recording on said tape said message characterizing sections at the reduced frequencies of transmission, means for blotting out said recorded message sections, and traveling pick-up means traveling at a speed higher than the speed of the tape in the ratio of the original message frequencies to the re-

duced transmitted message frequencies, said recording means and said blotting out means being spaced longitudinally of the path of said tape to permit said pick-up means repeatedly to pick up each characterizing message section between the time of its recording and the time of its blotting out whereby to reconstitute from each characteristic section the true message section characterized thereby.

9. In apparatus for transmitting messages, a rotary member carrying an endless recording tape and driven continuously at a preselected speed, means for forming on said tape, as it is driven, a true record of the message, a plurality of pick-ups, a common rotary carrier for said pick-ups, means driving said carrier at a speed such that the speed of the pick-ups is proportional to, but less than, the speed of the recording tape, means for rendering said pick-ups effective successively in timed relation whereby they pick up characteristic sections only of the syllabic wave trains composing the recorded message and effectively eliminate repetitious portions of each such syllabic wave train, the speed of driving of the pick-ups being so proportioned to the speed of the tape that the pick up time for each said characteristic section is substantially the same as the recording time for the entire syllabic wave train characterized thereby, and means, fed by said pick-ups, transmitting said syllabic characterizing sections to a distant station.

10. In apparatus for transmitting messages, a rotatable member, a recording tape mounted on said member for rotation therewith, a stationary recorder for recording each message on the tape as the tape is rotated, a second rotatable member, a plurality of pick-ups carried by said second rotatable member and operatively associated with said tape for picking up sections of a message recorded on said tape, driving means

- for said rotatable member constructed and arranged to rotate the tape and pick-ups relatively at a predetermined speed lower than the speed of the tape, means for rendering said pick-ups successively effective to pick up sections of the recorded message from the tape, the speed of rotation of the pick-ups relative to the tape and the movement of the pick-ups being predetermined to cause the pick-ups to pick up continuously at reduced frequencies only uninterrupted characterizing wave signal patterns of each syllabic wave train composing the message and thereby eliminate repetitious portions of each said syllabic wave train.
11. In apparatus receiving unintelligible syllable characterizing, uninterrupted wave signal patterns of a message transmitted at reduced frequencies, a rotatable member, an endless recording tape mounted on said member for rotation therewith, stationary means for recording on said tape said syllable characterizing wave patterns at the reduced frequency of transmission, a second rotatable member, a plurality of pick-ups carried by said second rotatable member and operatively associated with said tape for picking up the wave recorded on said tape, driving means for said rotatable members constructed and arranged to move the tape and pick-ups relatively at a predetermined higher speed than the speed at which the wave patterns were recorded on the tape, means for rendering said pick-ups successively effective to pick up the recorded wave patterns from said tape, the speed of rotation of the pick-ups relative to the tape and the number of pick-ups being predetermined to cause the pick-ups to repeatedly pick up at the original message frequency each syllable characterizing wave pattern whereby to reform from each such pattern the syllable characterized thereby.

THOMAS W. W. HOLDEN.
